ANDRAS CSEH, OF SOUTH NORWALK, CONNECTICUT.

DUMPING-RECEPTACLE FOR DIRT, RUBBISH, AND OTHER REFUSE.

1,115,403.

Specification of Letters Patent.

Patented Oct. 27, 1914.

Application filed May 6, 1914. Serial No. 383,743.

To all whom it may concern:

Be it known that I, ANDRAS CSEH, a subject of the King of Hungary, residing at South Norwalk, in the county of Fairfield and State of Connecticut, have invented certain new and useful Improvements in Dumping-Receptacles for Dirt, Rubbish, and other Refuse, of which the following is a specification, reference being had therein to the accompanying drawing.

This invention relates to dumping receptacles for dirt, rubbish and other refuse, and has for its object to provide a receptacle of such class, in a manner as herein-after set forth, having means whereby the dirt, rubbish or refuse collected therein, can be conveniently and quickly discharged therefrom.

Further objects of the invention are to provide a receptacle for the purpose set forth which is simple in its construction and arrangement, strong, durable, efficient and convenient in its use, readily set up and comparatively inexpensive to manufacture.

With the foregoing and other objects in view the invention consists of the novel construction, combination and arrangement of parts as hereinafter more specifically described and illustrated in the accompanying drawing, but it is to be understood that changes, variations and modifications can be resorted to which come within the scope of the claims hereunto appended.

In the drawings wherein like reference characters denote corresponding parts throughout the several views:—Figure 1 is a side elevation of a dumping receptacle in accordance with this invention; Fig. 2 is a front elevation, Fig. 3 a rear elevation, Fig. 4 a vertical sectional view, illustrating in full lines the bottom closed, and in dotted lines the bottom open for the purpose of discharging the contents of the receptacle.

Referring to the drawings in detail, the receptacle consists of a rear wall 5, a front wall formed of a stationary and a hinged section 6—7 respectively, a top 8 provided with an opening 8^a, side walls 9—10, and a bottom formed of a stationary section 11, and a movable section 12. The stationary section 11 of the bottom is secured to the side walls 9—10 and rear wall 5 above the lower edges thereof, and fixedly secured to the side walls 9—10, rear wall 5, and to the section 11 is an inclined plate 13.

Secured to the inner face of the section

7, inwardly with respect to each vertical edge of said section 7 is a triangular shaped member 14, and abutting against and secured to the base of each of said members 14, and further secured to the inner face of the section 7 is the section 12 of the bottom, the latter, when the bottom of the receptacle is closed, is in alinement with the section 11 of the bottom. Secured to the triangular shaped members 14 and to the bottom 12 is an inclined plate 15 which opposes the plate 13 and extends at an inclination in an opposite direction with respect to the direction of the plate 13, or in other words, the plate 15 extends toward the plate 13 at an inclination and forms, in connection with said plate 13, the lower portion of the V-shaped collecting chamber.

The section 6 of the front wall is secured against the side walls, and when the section 7 of the front wall is closed, it abuts against the side walls, and the triangular members 14, when the section 7 is closed, are positioned against the inner faces of the side walls 9—10. The section 7 of the front wall is hinged, as at 16, to the section 6.

Each of the side walls 9—10 has secured to its outer face a keeper 17, and shiftable through said keeper 17 are links 18, having their forward ends as at 19, pivotally connected to the angle-shaped ends 20 of a strap 21 which is fixedly secured by the hold-fast devices 22 to the outer face of the front wall.

The rear ends of the links 18 are pivotally connected as at 23 to the lower ends of a pair of levers 24, these latter being pivotally connected as at 25 to the outer faces of the side walls 9—10, and the said levers 24 have their upper ends pivotally connected, as at 26, to the arms 27 of a yoke-shaped handle 28, the latter being offset as at 29 to provide a grip. The handle 28 extends across the outer face of the rear wall 5 and is detachably connected thereto, by latch members 30, for the purpose of maintaining the section 7 of the front wall and the section 12 of the bottom closed.

When the handle 28 is shifted clear of the members 30, it can then be pulled rearwardly, shifting the levers 24 upon their pivots 25, moving the links 18 forwardly, and as the said links 18 are connected to the strap 21, it is obvious that the section 7 of the front wall will be projected forwardly, and said section 7 will carry the section 12 of the bottom and the plate 15

therewith, under such circumstances opening the receptacle and allowing the contents thereof to be quickly discharged therefrom.

Secured to the top 8 and extending through the opening 8^a, is a funnel-shaped mouth piece 31, having its inner end closed through the medium of a pair of counterbalanced, oppositely disposed closure members 32-33, which are hinged as at 34, to the inner face of the top 8 and carrying weights 34.

Each of the side walls of the receptacle has attached thereto a handle 35.

Molding strips 36 are secured to the edges 15 of the top 8 and overlap front, rear and side walls of the receptacle.

What I claim is:-

1. A device for the purpose set forth comprising a receptacle having a hinged front 20 wall section, a removable bottom section connected to said front wall section, an inclined plate connected to the said front wall and bottom sections, a stationary bottom section, an inclined plate secured to the rear wall of the receptacle and to said stationary section and disposed oppositely with respect 25 to the first mentioned inclined plate, means for projecting said front wall section forwardly to open the bottom of the receptacle to allow of the discharge of the contents thereof, and latches engaging with said means for maintaining said front wall section and removable bottom section in closed position.

means for projecting said front wall section forwardly to open the bottom of the receptacle to allow of the discharge of the contents thereof.

2. A device for the purpose set forth comprising a receptacle having a hinged front wall section, a removable bottom section connected to said front wall section, an inclined plate connected to the said front wall and bottom sections, a stationary bottom section, an inclined plate secured to the rear wall of the receptacle and to said stationary section and disposed oppositely with respect 40 to the first mentioned inclined plate, means for projecting said front wall section forwardly to open the bottom of the receptacle to allow of the discharge of the contents thereof, and latches engaging with said 45 means for maintaining said front wall section and removable bottom section in closed position.

In testimony whereof I affix my signature in the presence of two witnesses.

ANDRAS CSEH.
